CLAIM

The ornamental design for a telephone set, as shown and described.

DESCRIPTION

FIG. 1 is a top, front, left side perspective view of an embodiment of a telephone set at a first position of inclination according to the new design;

FIG. 2 is a left side view thereof;

FIG. 3 is a right side view thereof;

FIG. 4 is a right side view thereof in a second position of inclination;

FIG. 5 is a bottom perspective view thereof;

FIG. 6 is a rear view of the telephone set of FIG. 1 at the second position of inclination;

FIG. 7 is a rear, left side perspective view of the telephone set of FIG. 1 at the second position of inclination;

FIG. 8 shows a top view of a second variant of the telephone set of FIG. 1;

FIG. 9 shows a top view of a third variant of the telephone set of FIG. 1; and,

FIG. 10 shows a top view of the telephone set of FIG. 1.

The broken line showing portions of the telephone set is included for illustrating environmental structure and forms no part of the claimed design.
